U.S. Appl. No. 29/818,916, filed Dec. 10, 2021, Van Varick et al.
(Continued)*Primary Examiner* — Charles D Hanson*(74) Attorney, Agent, or Firm* — Sheridan Ross P.C.(57) **CLAIM**

We claim the ornamental design for a walking frame, as shown and described.

DESCRIPTION

FIG. 1 is a top front perspective view of a walking frame; FIG. 2 is a bottom rear perspective view of the walking frame of FIG. 1;

FIG. 3 is a front elevation view of the walking frame of FIG. 1;

FIG. 4 is a rear elevation view of the walking frame of FIG. 1;

FIG. 5 is a right side elevation view of the walking frame of FIG. 1;

FIG. 6 is a left side elevation view of the walking frame of FIG. 1;

FIG. 7 is a top plan view of the walking frame of FIG. 1;

FIG. 8 is a bottom plan view of the walking frame of FIG. 1; and,

FIG. 9 is a top rear perspective view of the walking frame of FIG. 1 in a folded state.

The broken lines in the drawings illustrate portions of the walking frame, which form no part of the claimed design.
